HEAD FOR COCK PLUGS

Carl R. Stone, Chicago, Ill., assignor to Crane Co.,
Chicago, Ill., a corporation of Illinois

Application September 4, 1942, Serial No. 457,250

7 Claims. (Cl. 251—101)

This invention relates to a new and improved actuating means and more particularly to an operating head for a cock or plug valve.

Heretofore, one of the difficulties in the manufacture of valves of this general type resided in the inability of obtaining uniform strength in the operating heads of the frusto-conical plugs. My invention therefore provides for a more evenly distributed metal therein and thereby minimizes the objectionable formation of cooling stresses with the net result that a handle or wrench may be applied to the operating head without reasonable fear that the integrally cast plug and head might be broken or cracked in so doing.

An important object of this invention is to provide a practical and economical plug head by reducing the heavy metal section of the formerly solid head and in so doing reduce substantially the amount of metal necessarily used and simultaneously reduce the large percentage of foundry scrap previously occasioned by using a solid head for these plugs applied to the kind of valves shown for example on page 92 of the No. 41 catalogue of Crane Co.

Another important object of this invention is the provision of a cock plug with integral head of materially less weight than heretofore and yet which dispenses with the intricate and expensive coring of prior heads while permitting the use of a regular wrench. However, it discourages the use of a pipe wrench or other unsuitable tools by reason of its outer cored surfaces or recesses.

Other and further important objects will become apparent from the disclosures in the following specification and the accompanying drawing, in which

Fig. 1 is a front elevation of the cock valve plug of this invention.

Fig. 2 is a side elevation of the plug of this invention taken at right angles to the elevation of Fig. 1.

Fig. 3 is a plan view of the plug as shown in Figs. 1 and 2.

Fig. 4 is a sectional view taken on the line 4—4 of Fig. 1.

As shown in the drawing, the general reference character "A" indicates a valve body in which the numeral 1 indicates the cock valve plug closure incorporating the instant invention and is provided with the customary inlet and outlet ports 2 and 3 and the elongated passageway 4 joining the ports 2 and 3. The plug 1 is provided with the novel head 6 having the radially extending ribs 7 formed by recessing portions of a full square head, as indicated, but addi-

tionally capped and strengthened, as hereinafter explained.

Manufacturing costs have been reduced by eliminating the usual high percentage of scrap originating in the foundry because of the shrinkage stresses previously accompanying the casting of solid heads for cock plugs. Critical study revealed that these stresses occurred at the junction between the central or body portion and the upper or head portion of the plug primarily because the body portion of the plug was cored above the passageway 4, as indicated by the dotted lines 5, with the result that the body portion of the plug was merely a shell having a hollow interior with comparatively thin wall sections of metal as compared with the upper solid head portion of the plug. It would seem that the obvious solution resided in coring the head as well as the plug. However this would entail intricate and relatively expensive coring. Also the problem would not be entirely solved inasmuch as a plug of the hollow head type in actual service might more easily be broken by the operating attendant who believing himself to be working with a solid and virtually unbreakable plug head might easily use a pipe wrench or other unduly heavy tool to operate the valve with the result that excessive torque would be exerted on the hollow head to cause breakage of the casting.

It was thus determined that the ultimate solution was not in coring but rather by way of a properly designed head in the pattern itself. After the segments 8 of the plug head 6 had been removed from the head by changing the pattern, it became evident that the plug head 6 with radial ribs 7 alone was not sufficiently strong to withstand the relatively high torque applied during the opening and closing operation of the cock or plug valve. It was discovered that a horizontally extending webbed portion 9 extending over and between the radially extending ribs 7 reinforced the head sufficiently to withstand any reasonable torque which an operator might apply to the valve in the course of operation.

The conventional ribs 11 and 12 were then provided on the webbed portion 9 to act as indicators for showing the positioning of the passageway 4 with respect to the body portion of the plug.

It should be observed that the edges of the ribs 7 in the head 6 of the plug provide corner portions 13 thereby permitting the use of a regular square hole wrench to engage this novel plug head.

It will be seen that herein is provided a novel

and very useful cock valve plug and one which is performing the very useful function of saving raw materials, and I am therefore aware that numerous details of construction could be varied throughout a wide range without departing from the principles disclosed herein, and I therefore do not propose limiting the patent granted herein otherwise than as necessitated by the prior art.

I claim:

1. A valve closure or the like having an upwardly extending actuating head for effecting rotative movement thereof, the said head having its sides relieved to form a plurality of substantially vertical intersecting walls, a horizontal top portion for the said head covering the central portion of the head and the relieved sides and walls.
2. A valve plug having an upwardly extending head portion, the said head portion having its sides relieved to form radially extending ribs, a web-like cover for the said head portion, the said ribs and web-like cover providing means for engagement of a wrench having a polygonal opening.
3. A valve plug or the like having an extension at one end thereof, the said extension comprising a solid central portion and radially extending ribs, a substantially horizontally extending web at the top of the said extension joining the said ribs.
4. A valve plug having an extension at one end

thereof, the said extension comprising a central portion and radially extending ribs forming a substantially X-cross-section, a web at right angles to the top portion of the said ribs, the said ribs and web adapted to receive a polygonal hole wrench for effecting rotative movement of the said plug.

5. A valve plug having an extension at an upper end portion thereof, the said extension comprising a central portion and radially extending ribs, a horizontal web at the top of said extension joining the said ribs, the said ribs being of substantially uniform length and thereby adapted to receive a wrench with a polygonal opening to effect rotation of the plug.
- 10 6. A valve plug having an extension at one end thereof, the said extension comprising a central portion and radially extending ribs, a web substantially covering the said extension and joining the said ribs, the said ribs being angularly arranged relative to each other and having substantially corner portions for receiving a wrench with a polygonal opening for positioning over the entire head.
- 20 7. A cock valve plug having an extension at one end thereof, the said extension comprising a central portion and radially extending ribs, a horizontal web at the top of and joining the said ribs, the said ribs forming corner portions for receiving a polygonal hole wrench engaging the rib corner portions.

CARL R. STONE.
